PRESSURE REGULATING VALVE FOR PUMPS

Carlos B. Livers, North Hollywood, Calif., assignor
to Bendix Aviation Corporation, North Hollywood, Calif., a corporation of Delaware

Application January 8, 1952, Serial No. 265,451

2 Claims. (Cl. 137—505)

1

This invention relates to pumping systems for supplying pressure fluid at a predetermined maximum pressure, and more particularly to a valve structure for automatically throttling the suction line of the pump when the output pressure tends to exceed the predetermined maximum pressure.

An object of the invention is to provide a simple and inexpensive, yet reliable valve for the purpose stated.

Another object is to provide an inexpensive valve for the stated purpose that maintains good regulation of the pump output pressure.

The foregoing together with more specific objects and features of the invention will become apparent from the description to follow.

The single figure of the drawing is a schematic diagram showing a pump equipped with a valve in accordance with the invention.

Referring to the drawing, the pump therein depicted comprises a body member 1 defining three pump cylinders 2, 3 and 4, respectively, containing plungers or pistons 5, 6 and 7 respectively, which are actuated by eccentrics 8, 9 and 10 respectively, on a common drive shaft 11. Each of the pump cylinders 2, 3 and 4 is provided with a spring-closed intake valve 12 which connects it with a common intake passage or manifold 14, and a spring-closed exhaust valve 13 which connects it with a common discharge passage or manifold 15. The discharge manifold 15 is to be connected directly to the load to be supplied from the pump. The intake manifold 14 is adapted to be connected directly to an inlet port 17 by a valve in accordance with the invention.

This valve comprises a hollow, cup-shaped cylindrical valve member 19 closed at its left end except for a fluid passage 20, and open at its right end. The valve member 19 is in sliding, sealing engagement with a cylinder 21 formed in the body 1. At its right end, the cylinder 21 is enlarged to provide an annular port 22 in constant communication with the intake passage 14 leading to the pump. The right end of the cylinder 21 defines an annular stationary sealing surface 24 surrounding the intake port 17. A spring 25 is contained within the valve member 19 and is compressed between the left end of the valve member and the right end of the cylinder 21.

The valve member 19, at its left end, bears against a cylindrical rod 26 which constitutes a piston in a bore 27 formed in the housing. Annular grooves 26a are preferably provided on the piston 26 to facilitate the circumferential equalization of pressure fluid on the piston and prevents lateral forces which would tend to bind it

2

and prevent its free movement. The left end of the bore 27 communicates with a chamber 28 which in turn is communicated by a passage 29 with the discharge manifold 15 of the pump. A cup-shaped screen 30 is provided in the chamber 28 to prevent solid particles in the fluid from reaching the piston 26. Such particles might tend to prevent free action of the piston. The screen 30 may be retained in sealing engagement with the right end of the chamber 28 by a helical compression spring 31 compressed between the left end of chamber 28 and an outwardly extending flange 30a on the right end of the screen 30.

The area of the piston 26 is so proportioned relative to the spring 25 that the spring 25 maintains the valve member 19 in open position away from the sealing surface 24 except when the pressure in the discharge manifold 15 rises to a predetermined value, whereupon the force acting on the left end of the piston 26 overcomes the spring 25 and moves the valve member to the right until its open end engages and seals with the annular sealing surface 24.

It will be observed that when the poppet 19 is in open position, as shown, there is a free passageway for fluid from the inlet port 17, past the right end of the valve member 19, into the annular port 22 and thence into the intake manifold 14 where it is supplied through the intake valves 12 to the three pump cylinders. However, whenever the pressure rises above the predetermined desired value in the exhaust manifold 15, the piston 26 is moved to the right, moving the valve member 19 with it, until the latter seals with the annular sealing surface 24, thereby preventing further entry of fluid from the intake passage 17 into the intake manifold 14, whereupon the pump pistons 5, 6 and 7 reciprocate without pumping any fluid, simply drawing a vacuum in the pump cylinders and the intake manifold 14.

The success of the valve described appears to be due in part to its poppet action and the fact that all pressure forces on the valve member 19 are balanced. The poppet action of the valve makes it impossible for the valve to over-shoot beyond closed position, since, when the valve member closes against the sealing surface 24 it is incapable of any further movement, and remains in that position until the pressure in the discharge manifold 15 and the chamber 28 drops to a value sufficient to permit the spring 25 to overcome the force acting on the left end of the piston 26, and again open the valve.

Effective pressure balance on the valve member 19 is attained in all positions. Thus it will be observed that any axial pressure on the right

end of the valve member is substantially balanced by an equal and opposite pressure on the left end, because of the connecting port 20 in the valve member. It is impossible for any unbalanced lateral forces to be produced, because the fluid passages or chambers associated with the valve member 19 are all symmetrical about the axis of the valve member. When the valve member 19 is closed on the annular sealing surface 24, and the pump is operating to draw a vacuum in the intake manifold 14, a substantial difference of pressure exists between the inside and the outside of the poppet. However this pressure acts symmetrically radially in all directions and cannot tend to cause the valve member to bind in the cylinder 21.

In valves of this type adapted for operation at relatively high pressures it is often difficult to secure a spring of sufficient stiffness and low spring rate to balance the pressures that are involved. This problem is solved in the present invention by virtue of the fact that the piston 26, which is exposed to the discharge pressure of the pump, can be of relatively small diameter as compared to the diameter of the poppet 19, and the spring 25 can be of relatively large diameter and length as compared to the diameter of the piston 26.

Although for the purpose of explaining the invention a particular embodiment thereof has been shown and described, obvious modifications will occur to a person skilled in the art, and I do not desire to be limited to the exact details shown and described.

I claim:

1. A pressure responsive flow regulating valve comprising: means defining a cylinder having an end port at one end and an annular port in its peripheral wall adjacent said one end, having an annular sealing surface surrounding said end port, and having a cylindrical bore of substan-

tially smaller diameter than said cylinder extending axially from its other end; means defining a pressure chamber at the end of said bore remote from said cylinder and in communication with said bore; a hollow cup-shaped cylindrical valve member reciprocable in said cylinder in sliding sealing relation therewith having an open end directed toward said one end of said cylinder that seals with said annular sealing surface in one, 5 closed, end position of the valve member and is spaced from said sealing surface in the other, open, end position, the other closed end of said valve member facing said bore; a helical compression spring extending and compressed between the closed end of said valve member and said one end of said cylinder for urging said valve member in opening direction; a piston reciprocable in said bore in sealing relation therewith and extending therefrom into said cylinder in contact with said closed end of said valve member, whereby the opening force of said spring on the valve member is opposed by the pressure force on said piston of fluid pressure in said chamber; and passage means communicating said other 10 end of said cylinder with said end port for equalizing the pressures on opposite faces of said valve member end wall.

2. A valve according to claim 1 in which the diameter of that portion of said valve member that seals with said annular sealing surface is substantially the diameter of said cylinder.
